UNITED STATES PATENT OFFICE.

WILLIAM HENRY CLARKE, OF SHEFFIELD, COUNTY OF YORK, ENGLAND,
ASSIGNOR TO JAMES HOWARTH & SONS, OF SAME PLACE.

DESIGN FOR A RASP OR FILE.

SPECIFICATION forming part of Design No. 17,413, dated June 28, 1887.

Application filed February 7, 1887. Serial No. 226,881. Term of patent 7 years.

To all whom it may concern:

Be it known that I, WILLIAM HENRY CLARKE, a subject of the Queen of Great Britain, residing at Sheffield, in the county of York, England, have invented and produced 5 a new and original Design for the Teeth of Rasps or Files, of which the following is a specification, reference being had to the accompanying drawings, forming part thereof. 10 Figure 1 is a perspective view of three of my teeth for rasps enlarged. Fig. 2 is a sectional elevation of a tooth and part of the body of the rasp enlarged. Fig. 3 is a representation of a horse-rasp having teeth of my design.

Heretofore the teeth of rasps and files have been made with a nearly vertical face, as A, terminating with a cutting-edge, as B, and having an inclined back of smooth contour.

The principal feature of my design is the 20 serrated outline or form of the back of the tooth, such serrated configuration giving the appearance of a larger number of teeth, as seen in the drawings, Fig. 1.

I claim—

25 The design for a rasp or file herein shown and described, the same consisting in the shape and configuration of the teeth having the vertical wall A, the terminal point or edge B, the sloping back C, and the serrations D E, as set forth.

WILLIAM HENRY CLARKE.
